GEORG MARTIN JULIUS ANSORG, OF DRESDEN, GERMANY, ASSIGNOR TO SÄCHSISCHE MASCHINENFABRIK VORM. RICH-HARTMANN AKTIENGESELLSCHAFT, OF CHEMNITZ AND DRESDEN, GERMANY.

PREPARATORY WORSTED SPINNING.

Application filed September 29, 1925, Serial No. 59,334, and in Germany December 12, 1924.

This invention relates to the class of worsted preparing machinery which is specially designed to produce the roving required for being spun into worsted yarn. 5 The particular object of this invention is to utilize a single set of fallers or gills of adequate construction in a most advantageous manner, so as to replace the porcupine or rotary faller hitherto used in the intermediate and finisher passages of worsted preparation sets.

The gill bars or fallers, in constituting the plain bed of gills of different width and depth, are universally recognized and used 15 as an appropriate means for drawing medium and long stapled fibrous materials.

Two methods of gilling are generally in use, either by the single or by the double set of fallers driven by square threaded revolving screws, commonly termed gill screws. The single gill box with one row of gills is operated so as to ensure a rectilinear insertion of the faller pins into the bulk of the fibres, whilst the intersecting gill 20 box fitted with a double row of gills works in such a way that the pins pierce the sliver from above and from below, thus preventing the fibres from escaping from the needle field, and constituting positive guiding 25 means whereby the fibres are thoroughly guided and presented to the drawing rollers, which, owing to their revolving at a higher rate of surface speed than the preceding feed rollers, accomplish the drafting process 30 required for the attenuation of the sliver.

The main object of any drafting of fibrous material is known to be the obviation of thick and thin places in the sliver by a certain number of doublings and of the subsequent drawing operation, on the other hand, however, the progressive regularization and attenuation of the sliver during the succeeding preparing passages, that is to reduce the number of fibres to the cross section and to parallelize the fibres until finally a roving is obtained having a sufficient grade of attenuation and a suitable hank weight, so as to be passed to the fine spinning frame.

50 For drawing thick woolen slivers before combing and in the first drawing passages of worsted mills, with which in the present case we are principally concerned, the double row of gills, as applied to intersect-

ing gill boxes, has entirely superseded the 55 single row of gills as well as the porcupine or rotary gill. Hence it is essential that the desired regularization of the sliver be achieved in these early stages of worsted preparation.

In the intermediate and finisher passages, 60 succeeding the intersecting gill boxes with a double row of gills, i. e. coarse or heavy drawings, reducers, intermediates, first and second finishers, where especially the attenuation 65 of the sliver and its transformation into suitable roving takes place, the porcupine has maintained its superiority and proved to be more useful than the double set of fallers, inasmuch as the application of 70 the latter to these passages is rather complicated and too expensive. In all worsted mills spinning on the Alsatian or French system of drawing, the faller was exclusively used up to the present for drawing 75 slivers which are still of a large cross section.

Practical experience now leads to the intuition that the double set of fallers, owing 80 to its difficult application, is no longer of use for drawing already reduced slivers in the intermediate and finisher passages of preparation, and that in this case the single set of fallers is far better adapted for this purpose. The single set of fallers ensures 85 not only a likewise positive conduction of the fibres in these reduced slivers, but also a more effective drawing operation in comparison with that of the porcupine, which presents less convenience in guiding the 90 fibres in the same perfect manner required for equal drafting than the single set of fallers constituting the plain bed or gills. This consideration might be quite sufficient 95 to show that the single set of fallers in an appropriate design might be applied to advantage for substituting the porcupines hitherto used in the intermediate and finisher passages of worsted preparation, so that in course of time these can be entirely dispensed with. This is the fundamental idea and basic principle of the present invention.

The attenuation of the sliver in the various worsted preparing operations on the Alsatian or French drawing principle is performed in conjunction either with endless rubbing leathers having imparted thereto both a forward and a reciprocating rubbing 100 105

motion, or with a revolving funnel for putting a false twist into the sliver, so as to compensate for the loosening of the internal structure of the sliver after drafting and to restore to the same the required tensile strength for treatment in the following passages.

The repeated process of re-strengthening the sliver must be also maintained when working with the single set of fallers in the intermediate and finisher passages of the worsted preparation.

This improved drafting method offers the possibility of realizing the application of much higher drafts than the porcupine or rotary drawing, whilst the uniformity of the roving remains unaffected and might be even improved. A further advantage is the increased working speed which means a considerable increase in production. In consequence thereof the application of higher drafting also affords a reduction in the number of the various preparing passages, this is in contradistinction to the porcupine system of drawing, which allows no such economy at all. The entire suppression of a plurality of passages contributes greatly to a remarkable economy in the operating costs of a worsted mill.

The scheme of the new drafting system with a single set of fallers operated, for instance, in conjunction with rubbing aprons and revolving funnel, is illustrated in the accompanying diagram; and referring thereto:

a, b indicate the slowly rotating pair of feed rollers for feeding the sliver on to the machine; *c, d* indicate the pair of sliding rollers to be positioned in front of the single set *e* of fallers (bed of gills); *f, g* the pair of drawing rollers rotating with increased surface speed, and *h, i* the two endless rubbing leathers having a rotary as well as a reciprocating lateral movement; *k* is the revolving

funnel which may be either single or double, 45 for final delivery of the attenuated and re-strengthened sliver to the drawing-off or bobbin roller, by means of which it is wound on to a bobbin; and *l* is the drawing-off roller imparting motion to the bobbin *m*. 50

With regard to the general construction of the drawing box with rubbers and a single row of gills for the intermediate and finisher worsted preparing passages, it should be observed that the heads or sections are arranged in an uninterrupted succession in the same manner as with the usual type of porcupine drawing boxes, whereas the intersecting gill box working with 2 sets of fallers can be only made with independent or isolated heads.

Further provision can be made in the arrangement of the heads of the rubber drawing box with a single row of gills that 2 to 4 and even more slivers can be separately 65 passed through the heads according to gradually increasing attenuation in the various passages of worsted preparation.

Claims:

1. In a drawing box having means for effecting rubbing motion for preparatory worsted spinning, a set of fallers constituting one single bed of gills for the intermediate and finisher passages in combination with a pair of rub aprons, substantially as 75 and for the purposes set forth.

2. In a drawing box provided with means for effecting rubbing motion for preparatory worsted spinning, a set of fallers forming one single bed of gills for the intermediate and finisher passages in combination with a pair of rub aprons following said gills, and a revolving funnel for producing the false twist, substantially as and for the purposes set forth. 85

In testimony whereof I affix my signature.

GEORG MARTIN JULIUS ANSORG.
